UNITED STATES PATENT OFFICE.

FELIX B. TAIT, OF DECATUR, ILLINOIS.

CHECK-ROW CORN-PLANTER.

SPECIFICATION forming part of Letters Patent No. 245,028, dated August 2, 1881.

Application filed November 22, 1880. (Model.)

To all whom it may concern:

Be it known that I, FELIX B. TAIT, a citizen of the United States, residing at Decatur, in the county of Macon and State of Illinois, have 5 invented a new and useful Improvement in Check-Row Corn-Planters, of which the following is a specification.

My invention relates to improvements in check-row corn-planters in which the dropping mechanism is operated by a wire or cord having knots or stops thereon; and it consists, first, in the arrangement of a four-tooth ratchet-wheel and a pawl pivoted to an oscillating arm to impart an intermittent rotary motion to the 10 transverse shaft that operates the seed-disks by the action of the knots or stops of the wire or cord on the fingers thereto attached; second, of a weighted pawl so constructed and arranged as to lock the ratchet and driving 15 pawl at the terminus of each forward stroke; third, the combination of the above devices with suitable gearing for operating the seed-disks and lower drops. I attain these objects by the mechanism illustrated in the accompanying drawings, in which—

Figure 1 is a transverse vertical section on the dotted lines $\alpha\alpha$, Fig. 5. Fig. 2 is a bottom view of circular plate, showing gearing and teeth for operating lower drop. Fig. 3 is an 20 end view of four-tooth ratchet-wheel and double pawls before stroke is made. Fig. 4 is an end view of Fig. 3, showing position of parts after stroke is made and the parts locked. Fig. 25 5 is a plan of Fig. 3, showing shaft and pinion-wheel that operates the seed disks or plates, the seed box or plates shown by dotted lines. Fig. 6 is an end view, showing the guides on the bar and the wire as applied. The dotted lines represent the terminus of its back stroke.

40 A is the seed-box constructed in the usual manner. B is a perforated seed-disk.

C is a circular plate provided with beveled gear c on the under side, and also with internal teeth, $c' c'$.

45 D is the seed-tube, and E the furrow-opener. This seed-tube is open in the back part. F is a lever-valve pivoted at f , the lower part, f' , of which is bent so as to fit the inside of the tube, and retains the corn until the lever-valve 50 is opened by the upper end impinging on the teeth $c' c'$.

G is a shaft preferably made of iron tubing.

H is a bevel-pinion thereon that engages with the bevel-gear c . I is a four-tooth ratchet-wheel fastened to the end of the shaft G. J is a plate 55 fastened to the frame j .

K is a pivoted arm or lever swinging on the shaft between the plate J and the ratchet-wheel I. This arm is provided with fingers k k , Fig. 5, in which the check-row wire or cord 60 is placed. L is a pawl pivoted on the arm K. M is a weighted pawl pivoted to the lower extremity of the plate J, and is designed to stop the rotation of the shaft G by terminating the forward stroke of the pawl L, thus forming a 65 dead-lock or stop to the entire dropping mechanism, as its motive power is dependent on the arm and fingers K and k k , and which does in turn receive its motion from the knots or stops on the wire or cord that is stretched across 70 the field.

By reference to Fig. 6 on second page of drawings it will be seen that the wire or cord does not cross the planter, but passes along the side. The pulleys Q serve as a guide to the 75 wire or cord, as does also the pulleys P p to keep it between the fingers k k of the arm K, while the arm is vibrated forward and back by the stops on the wire and the spring.

The operation is as follows, viz: The check-row wire or cord provided with suitable knots or stops (the distance apart it is desired to plant the hills of corn) is placed in the forked fingers k k . As the machine is drawn across the field the knots cause the arm to vibrate 80 from the position shown in Fig. 3 to that shown in Fig. 4. The arm being pivoted on the shaft is returned by a suitable spring for another stroke to the position shown in Fig. 3. By the vibration of this arm the pawl L, which is engaged with one of the teeth of wheel I, causes 85 the ratchet to turn one-fourth of a revolution. As the ratchet revolves the tooth impinges on the inside of the lower arm, m' , of the pawl M, and lowers the point until after the following 90 tooth passes the end of the lower arm. When the arm and lever are in the position shown in Fig. 4 they form a lock or stop to prevent any further movement by the pawl L fitting in between the ratchet-wheel and the inside of 95 the pawl M at m'' , forcing the lateral projection of the pawl up against the ratchet-wheel at m' , thus forming a lock to the shaft. This pawl has a weighted projection, N, so as to 100

retain it in the position shown in Fig. 3, after the pawl L is lifted from its locked position. This movement of the ratchet revolves the shaft one-fourth turn, thereby operating the plate C through the pinion H and bevel-gear c. This causes the plate C to revolve. This plate has a nut, c", the upper end of which is made square or oval, and with a corresponding recess in the upper plate, B, so as to cause said plate to revolve therewith. The corn passes through the perforations b b into perforations in the plate C, and thence to the lower drop, the internal teeth, c' c', opening the lower drop by impinging in the upper end of the lever-valve F.

The devices shown are used in duplicate at each end of the shaft, so as to plant two hills of corn at one time.

The ratchet-wheel, with its pawls and shaft, can be used with other intermediate devices between the shaft and the mechanism in the seed-box, and the plate C and lever-valve F can be used with other mechanism to cause the plate to revolve.

I am aware that prior to my invention check-row attachments have been made with transverse shaft having ratchets for transmitting

motion thereto. I therefore do not claim such a combination, broadly; but

Having thus described my invention, what I claim as new, and desire to secure by Letters Patent, is—

1. In a check-row planter having a transverse shaft, in combination with a four-tooth ratchet-wheel, the pawl L, attached to the pivoted arm K, and the weighted locking-pawl M, pivoted to the plate or hanger J, substantially as and for the purpose set forth.

2. In a check-row planter, the combination, with the transverse shaft G, of the ratchet I, arm K, pawl L, weighted locking-pawl M, and plate or hanger J, in their relative positions, substantially as herein shown, and for the purpose described.

3. In a check-row planter, the combination, with the transverse shaft G and bevel-pinion H, of the seed-plate C, having corresponding teeth c on its face, and of the cam-shaped groove c', to operate the lower drop, substantially as shown and described.

FELIX B. TAIT.
